UNITED STATES PATENT OFFICE.

FRED BARNOFSKY, OF NOME, TERRITORY OF ALASKA.

SAFETY-RAZOR-BLADE HOLDER.

Application filed July 10, 1924. Serial No. 725,218.

To all whom it may concern:

Be it known that I, FRED BARNOFSKY, a citizen of the United States, and a resident of Nome, in the Territory of Alaska, have invented certain new and useful Improvements in Safety-Razor-Blade Holders, of which the following is a specification.

This invention relates to a holder for safety razor blades and has for its object 10 the provision of a device which will support blades of the Ever-ready or Gem type during honing and stropping.

A further object of the invention is the provision of a holder for safety razor blades 15 equipped with a locking device which may be readily released by the pressure of the fingers for permitting ready removal of the blades.

This invention will be best understood 20 from a consideration of the following detailed description, in view of the accompanying drawing forming a part of the specification; nevertheless it is to be understood that the invention is not confined to 25 the disclosure, being susceptible of such changes and modifications which shall define no material departure from the salient features of the invention as expressed in the appended claims.

30 In the drawings:

Figure 1 is a longitudinal side view of a holder with a blade locked in position.

Figure 2 is a longitudinal vertical section through the shank of the holder.

35 Figure 3 is a view in perspective of the device for locking the blade in position on the holder.

Figure 4 is a plan view of the blank from which the locking device is constructed.

40 Figure 5 is a plan view partly in section of the blade holder.

Referring more particularly to the drawings, 1 designates a handle having a cylindrical shank 2, which is bifurcated to form legs 3 and 4. The inner portions of the legs adjacent the slit 5 are cut away, as shown at 6, to form a seat for the upper end of a razor blade 7. The lower edges 50 of the legs at the bottom of the seat 6 are substantially in alinement for rigidly gripping the blades. The extreme outer end, beyond the seat 6 of the legs, is cut away, as shown at 8, whereby the blades 55 may be readily inserted between the legs and located in the seat 6. To aid in the

insertion of the blades the inner faces of the blades are flared, as shown at 9.

The outer faces of the legs adjacent their ends are provided with a reduced cylindrical portion 10 which is adapted to receive a sleeve 11 substantially rectangular in cross section. The outer faces of the legs adjacent their ends have raised curved portions 12 which are curved outwardly 65 and inwardly to form a rounded portion over which the curved ends 13 of a pair of tongues 14 ride. These tongues 14 are formed integrally with the sleeve 11 and are stamped from the blank 15 shown in 70 Figure 4. The ends 16 of the blank are brought together and welded or soldered, as may be desired.

A bar 17 has a reduced inner end 18 adapted to be received within a socket 19 formed 75 longitudinally in the handle 1 and in line with the flat upper surface 20 of the shank 2. The rod 17 is flat and adapted to lie upon the flat surfaces 20 of the legs 3 and 4 and has its outer end inserted through the 80 sleeve and bent outwardly and upon said sleeve as shown at 21 and secured in any approved manner by welding or riveting to said sleeve.

The legs 3 and 4 are provided with adjacent engaging lugs 22 between the outer end of the legs and the seat 6 for a purpose 85 which will be presently explained.

The operation of my device is as follows:

The sleeve 11 is removed from the position 90 shown in Figures 1 and 5 by pressing upon the shoulders 23 formed by the curving of the tongues 14 when the curved portion 13 of the tongues will ride outwardly and inwardly upon the curved surfaces of the upstanding portions 12 of the legs. This will cause the sleeve 11 to move outwardly towards the end and will move the bar 17 and withdraw the projection 18 from the socket 19 of the handle. The legs may then be sufficiently spread apart to remove the blade 7.

In replacing the blade in its seat 6 formed between the legs 3 and 4, the legs are forced open and the blade inserted through the slotted portion 5 and into the seat 6 with the lower end 24 of the blade projecting from the shank 2. The ends of the legs are then inserted through the sleeve 11 with the bar 17 sliding upon the flat portions 20 of the legs until the reduced portion 18 of the bar 17 will seat within the recess 19 and the inner end of the sleeve 11 will engage the 105 110

annular shoulder 25. While the sleeve is moving over the outer free end of the legs 3 and 4 the sleeve is compressing the legs toward each other and forcing the projections 22 into rigid engagement and thereby locking the blade in position within the seat 6. The upper end of the blade is adapted to engage the bar 17 to prevent loss of the blade between the legs.

10 What I claim is:

1. A blade holder comprising a handle and a bifurcated shank, the legs of the bifurcated shank having their inner adjacent portions cut away to form a seat, the inner adjacent portions at their outer ends being cut away thereby forming inwardly projecting lugs, a sleeve adapted to receive the free ends of the legs and force the same inwardly towards each other, and tongues projecting 20 from the sleeve and adapted to engage the outer ends of the legs.

2. A blade holder comprising a handle and a bifurcated shank, the legs of the bifurcated shank adjacent their free ends having 25 an annular reduced portion, the legs beyond the reduced portion having a rounded enlargement, said legs being provided with a seat therebetween to receive a blade, a sleeve mounted on the annular reduced portion and provided with curved tongues engaging the rounded enlargement of the legs, pressure on 30 the tongues causing said tongues to ride over the enlargements and release the collar from the legs.

3. A blade holder comprising a handle and a bifurcated shank, the legs of the bifurcated shank adjacent their free ends having an annular reduced portion, the legs beyond the reduced portion having a rounded 40 enlargement, said legs being provided with a seat therebetween to receive a blade, a sleeve mounted on the annular reduced portion and provided with curved tongues engaging the rounded enlargement of the legs, pressure on 45 the tongues causing said tongues to ride over the enlargement and release the collar from the legs, and a rod connected to the collar and straddling longitudinally the legs.

4. A blade holder comprising a handle

and a bifurcated shank, the legs of the bifurcated shank adjacent their free ends having an annular reduced portion, the legs beyond the reduced portion having a rounded enlargement, said legs being provided with a seat therebetween to receive a blade, a sleeve mounted on the annular reduced portion and provided with curved tongues engaging the rounded enlargement of the legs, pressure on the tongues causing said tongues to ride over the enlargement and release the collar from the legs, and a rod connected to the collar and straddling longitudinally the legs, the handle being provided with a recess, a projection on the rod adapted to be seated in said recess.

5. A blade holder comprising a handle and a bifurcated shank, the legs of the bifurcated shank adjacent their free ends having an annular reduced portion, the legs beyond the reduced portion having a rounded 70 enlargement, said legs being provided with a seat therebetween to receive a blade, a sleeve mounted on the annular reduced portion and provided with curved tongues engaging the rounded enlargement of the legs, pressure on 75 the tongues causing said tongues to ride over the enlargement and release the collar from the legs, lugs on the inner faces of the legs projecting toward each other and adapted to be forced into engagement with each other 80 by the sleeve on the legs.

6. A blade holder comprising a handle and a bifurcated shank, the legs of the bifurcated shank adjacent their free ends having an annular reduced portion, the legs beyond 85 the reduced portion having a rounded enlargement, said legs being provided with a seat therebetween to receive a blade, a sleeve mounted on the annular reduced portion and provided with curved tongues engaging the rounded enlargement of the legs, pressure on 90 the tongues causing said tongues to ride over the enlargement and release the collar from the legs, said tongues being formed integrally with the inner end of the sleeve 95 bent forwardly and projecting beyond the outer end of said sleeve.

FRED BARNOFSKY.
